UNITED STATES PATENT OFFICE

2,623,397

DRIVE FOR A ROTARY MEMBER

James Eckersley Battersby, London, England, assignor to Masson Scott & Company Limited, London, England

Application August 11, 1948, Serial No. 43,638
In Great Britain August 18, 1947

7 Claims. (Cl. 74—228)

1

The present invention relates to an improvement in cross cutters for cutting a uniformly moving web of paper or the like and which cutters include a rotatable knife cooperable with a stationary knife with the rotary knife being spirally mounted so that the web or webs are progressively severed across the width thereof.

The invention particularly relates to the mounting of the knife means and the driving of the same.

More particularly the invention relates to the specific disposition of a frame carrying the knife means with respect to the main frame of the machine.

In order to obtain a square cut with an arrangement of the above kind, the axis of the rotary knife member must be inclined with respect to the longitudinal axis of the web, the angle varying in accordance with the respective knife and web velocities, requiring an adjustable mounting of the drum or equivalent knife-carrying member and appropriate construction and arrangement of the drive to accommodate such adjustments.

It has been customary in the past to drive the knife drum or equivalent knife-carrying member through a bevel gear on one end of the drum shaft meshing with a bevel pinion on a vertical driving shaft, the drum bearings being arranged so that they may be adjustably displaced upon their supports about the axis of the said vertical shaft. One of the drawbacks of this form of drive is that the drive mechanism is relatively complicated and therefore expensive, and further the cutter drum and bed plate require to be bodily displaced to a considerable degree in order to vary the inclination of its axis within the required limits.

It is one of the objects of the present invention to provide an improved form of drum or cutter mounting and drive therefore by virtue of which the required adjustments are accomplished by a reduction of the distance through which the drum and bed plate are required to be displaced.

According to the invention, a rotary cutting means of the kind described is mounted for adjusting movement to vary the inclination of the cutter with respect to the web path and is driven by belt or rope means, preferably multiple belts or ropes in conjunction with correspondingly grooved pulleys, disposed about the axis of adjusting displacement. In the preferred arrangement multiple belts of V section, engaged in correspondingly grooved pulleys are employed.

According to a further feature of the inven-

tion, the driving belt, or group of belts, is disposed to lie in a plane substantially parallel to the axis of rotation of the cutting means and preferably in a plane also passing through or near the cutting edge of the stationary or dead knife.

The arrangement requires the belt pulley to be mounted on a shaft at right-angles to the drum shaft and driving the latter through gearing, preferably worm gearing.

According to a further feature of the invention, the vertical axis about which the pivotal adjusting movement of the drum is effected is disposed to one side of the drum shaft and in a vertical plane which passes through or near the edge of the stationary or dead knife. In the preferred arrangement, the bearings for the rotary knife drum and the V pulley driving the drum shaft are carried by a cradle or frame which is mounted for adjusting movement about a vertical fixed pivot in the main framework. The said fixed pivot is located to one side of the drum shaft as described above and the V drive pulley is arranged so that the belts are disposed symmetrically about the axis of the said pivot. The V drive pulley shaft may conveniently be carried in a frame constituting an extension or part of the frame carrying the main bearings for the drum, and a worm gear is provided for transmitting the drive from the said shaft to the drum shaft. A coupling may be interposed between the worm gearing and the drum shaft.

The V pulley associated with the cutter drum shaft will generally be driven from a similar pulley located vertically beneath it, and the said lower pulley may be associated with some form of infinitely variable gear through which the drive is taken. Alternatively the V pulleys themselves may be variable to provide the necessary speed changes. It will be appreciated that the V pulley associated with the drum shaft will be displaced when the latter is displaced to vary the general inclination of the cutter, and such displacement will involve relative angular movement of the planes of the two V pulleys. Such angular differences will, however, be relatively small and readily accommodated by the belts without interfering in any way with the drive transmitted thereby.

By this mode of drive the vertical pivot about which the knife drum assemblage is adjusted may be located as near as practicable to the drum and a relatively simple and compact drive arrangement is afforded.

2

In the accompanying drawings:

Figure 1 is a side view of the driving end of the machine according to the invention.

Figure 2 is an end view, and

Figure 3 is a somewhat diagrammatic plan of the driving end of the machine showing the drum and stationary blade inclined to the direction of web travel.

In carrying the invention into effect according to one convenient mode, described by way of example, a rotary drum 1 carrying a cutting knife 1a of spiral form (the spiral shape being only just perceptible owing to the scale of the drawings), adapted to co-act with a stationary or dead knife 2 for severing sheets from a web or webs of paper 15 or other material is supported in end bearings 3 only one of which is shown, mounted upon a frame or cradle 4 supported on the main framework 5 of the cutting machine. The said cradle frame 4 also carries the stationary knife 2 which is arranged to one side of the drum shaft. On the same side of the drum shaft and beyond the shaft bearing, the cradle frame 4 has a bracket 6 formed with a vertical bore, which may be in a boss provided on the bracket, fitting over a vertical fixed pivot pin 7 carried in a bracket 5a bolted to the main supporting framework 5, so that any displacement of the cradle frame 4 is constrained to take place about the axis of such pivot pin 7 which axis lies in a vertical plane 25 parallel to the vertical plane containing the axis of the drum 1 and passing near to the cutting edge of the stationary knife 2. At the same end of the drum, the drum shaft 8 extends beyond its bearing 3 and is connected by a coupling 9 to a worm gear drive 15 the driving shaft 11 of which is horizontal and at right-angles to the drum shaft 8. The bearings for this shaft 11 and of the worm gear are also carried by the bracket 6 which is provided with the pivot bore. A V-grooved pulley 12 is mounted on the horizontal shaft 11 and is disposed so that the central plane of the pulley coincides with the pivot axis of the pin 7 and the belt grooves are disposed symmetrically on either side thereof. The pulley 12 has 45 multiple V grooves and belts which are driven from a second V groove pulley 13 mounted vertically beneath the first. The said lower pulley 13 may conveniently be mounted on the final shaft of an infinitely variable gear 14 such as a 50 Reeves type gear, the drive being taken from the main drive shaft of the machine. As shown, this lower pulley means 13 is mounted so that the mean or central plane thereof coincides with the axis of the pivot 7.

Instead of the gear 14, the necessary speed changes may be effected by the V pulleys being themselves variable as to diameter.

The stationary cutting knife is generally arranged to one side of the drum and below the axis 60 thereof, the web to be severed being fed thereto in a downwardly inclined direction, by feeding rolls, preceded if necessary by rotary slitter knives 15 which divide the web longitudinally. After the sheets have been severed by the rotary knife they 65 pass to conveyor means and thence, if desired, to an automatic stacking device. The feeding rolls and slitter knives are generally carried by the main framework on which the rotary knife is also carried and may be driven from the afore-70 said main shaft by multiple V belts or ropes. It will be understood that the cradle frame carrying the rotary knife is also adjustable through horizontal displacement upon the main framework, such adjustment being effected by suit- 75

able screw devices in conjunction with clamping means.

Since the general arrangement and mounting of the rotary cutting means may be widely varied in accordance with practical requirements it will be appreciated that the drive arrangement described above may be modified accordingly. Whilst the amount of power required for cutting will generally necessitate the use of multiple driving belts, circumstances may occur in which a single belt is sufficient, or rope drives may be employed.

I claim:

1. A drive arrangement for an angularly adjustable rotary member comprising a main frame, a secondary frame, a rotary member rotatable about a horizontal axis carried by said secondary frame, a cradle embodied with said secondary frame and extending longitudinally of the axis of the member, a fixed bracket extending laterally of the main frame beneath said cradle, said fixed bracket carrying a vertical pivot, said pivot being disposed laterally of the axis of rotation of the rotary member and at least closely adjacent the main frame, said cradle having a vertical aperture therein receiving and journaling said pivot whereby said secondary frame is swingable about said pivot with respect to said main frame, a shaft carried by said cradle at right angles with respect to the axis of rotation of said rotary member, said shaft being mounted above said vertical pivot, pulley means carried by said shaft, the mean plane of said pulley means coinciding with the axis of said vertical pivot, second pulley means mounted on said main frame beneath said vertical pivot and belt means trained about both said pulleys with the runs thereof passing on opposite sides of said vertical pivot and means for imparting variable speed to said pulley means, the arrangement being such that the closer the vertical pivot axis is disposed with respect to the main frame the less bodily displacement of the secondary frame with respect to the main frame is required and the less twisting of the belt means relative to the pulley is effected in order to provide a given angular variation of the rotary member relative to the main frame.

2. A drive arrangement for an angularly adjustable rotary member comprising in combination with a main frame, a cradle supporting the rotary member, a pivot means carried by the main frame and disposed in a plane that is laterally offset with relation to the plane containing the axis of the rotary member, means connecting the cradle to the pivot so that the cradle can swing thereabout, the location of the pivot with respect to the axis of the rotary member permitting maximum angular adjustment of the member with minimum swinging of the cradle, spaced pulley means for driving the rotary member respectively carried by the cradle and the main frame with the mean plane thereof coinciding with the axis of the pivot means and the plane of the pulley carried by the cradle being parallel to the axis of the rotary member, flexible drive means trained over said pulley means and passing symmetrically on opposite sides of said pivot axis, and the location of the pulley means with respect to the pivot axis minimizing misalignment of the pulley means when the cradle is angularly adjusted with respect to the main frame.

3. An angularly adjustable rotary member and

drive therefore comprising a main frame, a cradle movable thereon, said rotary member being supported by said cradle, said cradle including an extension projecting laterally of said frame, pivot means supported by the frame and connected with said extension, said pivot means being located closely adjacent said frame and laterally offset with relation to the axis of the rotary member, a drivable shaft carried by said extension and disposed perpendicular to the axis of said rotary member, means connecting said shaft to the rotary member for driving the same, a first pulley means carried by said shaft and disposed in a plane parallel to the axis of the rotary member and said pulley means being located above and with its mean plane coinciding with the axis of said pivot means, a second driven pulley means carried by the main frame beneath said pivot means and disposed in a plane perpendicular to said main frame, with the mean plane of said second pulley means coinciding with the axis of the pivot means and flexible drive means trained over both said pulley means and passing symmetrically on opposite sides of said pivot axis, the arrangement being such that the location of the pivot means closely adjacent the main frame and with respect to the axis of the rotary member and the location of the pulley means with respect to the pivot axis permitting maximum angular adjustment of the cradle relative to the main frame with minimum bodily displacement and minimum misalignment of the pulley means.

4. A drive arrangement as defined in and by claim 2 in which the pulley means comprise multiple grooved pulleys and the flexible drive means comprise multiple V-belts.

5. A drive arrangement as defined in and by claim 2 and a worm gear drive connected between the first mentioned pulley means and the rotary member.

6. A drive arrangement as defined in and by claim 2 and an infinitely variable gear means operably connected with said second mentioned pulley means.

5 7. A drive arrangement for an angularly adjustable rotary member comprising angularly movable supporting means for supporting said member including a pivot means laterally offset with respect to the axis of the rotary member and belt and pulley drive means for rotating said member including a first pulley means also carried by the supporting means located above said pivot means with its axis perpendicular to the axis of the rotary member and its mean plane coinciding with the axis of the pivot means and a second pulley means located beneath said pivot means also with its mean plane coinciding with the axis of the pivot means and belt means trained over both said pulley means and passing 10 symmetrically on opposite sides of said pivot means.
